APPARATUS FOR ESTABLISHING A STANDARD CRANIAL POINT OF ORIENTATION

Edgar W. Snell, San Francisco, Calif.

Application November 17, 1933, Serial No. 698,529

13 Claims. (Cl. 33—174)

The present invention relates to an apparatus for establishing a standard cranial point of orientation of living persons that is absolutely constant, and its principal object is to enable the accurate measuring of the human cranium and other parts of the human anatomy from this established point of orientation.

A further object of the invention is to make it possible by subsequent registration to re-establish the same point of orientation of the same person at a subsequent time.

Further objects and advantages of my invention will appear as the specification proceeds.

The preferred form of my invention is illustrated in the accompanying drawing, in which—

Figure 1 shows my apparatus in vertical section taken along line 1—1 of Figure 2, a part of the apparatus being shown in side elevation, and the method being also illustrated;

Figure 2 a horizontal section and part plan view of my apparatus as viewed from line 2—2 of Figure 1;

Figure 3 a front view of my apparatus;

Figure 4 a fragmentary top plan view of a rear portion of my apparatus;

Figure 5 an enlarged side elevation of a stabilizer used in connection with my invention; and

Figure 6 an end view of the stabilizer.

While I have shown only the preferred form of my invention, I wish to have it understood that various changes or modifications may be made within the scope of the claims hereto attached without departing from the spirit of the invention.

To fix a cranial point of orientation, I first cause the head to assume a fixed position, and then establish three different planes, the horizontal plane of the pupils of the eyes, a median vertical plane between the pupils of the eyes and a transverse vertical plane defined by the glabella (the most anterior part of the forehead) and the point at which these three planes meet is my cranial point of orientation from which the different measurements desired may be taken.

The apparatus used for this purpose is illustrated in the drawing, and comprises a horizontal platform 1 having suitable means indicated at 2 for raising and lowering the same, and having a mirror 3 mounted vertically on the front portion thereof, while a light chamber 4 is mounted on the rear portion of the platform and is provided with a light 5 and an opening 6 through which light rays may pass toward the mirror. The mirror itself is formed with a horizontal slot 7. Two boxes 8 and 9 are inter-

posed between the mirror and the light chamber, and these boxes are disposed on opposite sides of a vertical median plane passing through the center of the mirror and the center of the light. The two boxes are mounted on wheels 10 adapted to ride on transverse rails 11, and the two boxes may be moved in opposite directions toward and away from the vertical median line of the apparatus by means of the screws 12 mounted in bearings 13 and threadedly engaging nuts 14 secured to the boxes respectively, the screws being threaded in opposite directions on opposite sides of the median plane. One of the screws may be operated manually by the handle 15, while the same movement is transmitted to the other screw through the chain 16. The two boxes are interconnected by expansible closures in the nature of hinged gates 17 which prevent the light from passing through the space between the boxes irrespective of the distance between the boxes. Each box comprises a front end piece 18, a rear end piece 19, and intermediate partitions 20 and 21, and the end pieces and the partitions are formed with horizontal slots 22, which lie in the same horizontal plane with the slot 7 in the mirror, all the slots being narrow, preferably $\frac{1}{8}$ of an inch in height. Sliding gates 23 are provided in connection with at least some of the partitions whereby the slots may be covered up.

It will be noted that the slots do not commence immediately adjacent the inner walls of the boxes, and small sections 24 are left immediately adjacent the inner wall of the box through which the slots do not extend. These small sections are provided with small perforations 25, which are also in alignment with one another, and lie in the horizontal plane of the slots in the mirror and in the boxes respectively, so that they may be viewed by a person looking through the slot in the mirror provided they are made to register with the eyes of the person.

The two boxes may be locked in adjusted position by means of a slotted member 26 secured on top of one of the boxes as at 27, and projecting over the other box and adapted to slidably receive a bolt 28 projecting from the other box and to be clamped to the latter by means of a wing nut 29. Each of the boxes has also secured to its top a clip 30 which projects over the light housing and is formed with a perforation 31 lying in the same vertical plane as the perforations 25 so that after the distance between the perforations 25 has been established, a piece of paper 32 may be placed under the clips 30 and punctured through the perforations 31 so as to

give a permanent record of the spacing between the perforations 25. A stop 32' positions the paper.

The mirror 3 has a standard 33 rising vertically therefrom, and a bar 34 extends horizontally from the standard and has a pendulum 35 pivoted thereto as shown at 36. The upper end of the pendulum is pointed as at 37 and adapted to ride over a scale 38, the pendulum being in a vertical position when the pointer points to the center of the scale as shown in the drawing. The pendulum 35 has an arm 39 projecting forwardly therefrom and this arm is weighted as at 40 to urge the lower portion of the pendulum in a forward direction.

The bar 34 also serves as a supporting means for two arms 41 extending horizontally in opposite directions, each arm having, at equal spacing from the median plane, a pendulum 42 suspended therefrom as at 43, each pendulum being actuated by a weight 44, to swing toward the median plane, and each pendulum being provided with a pointer 45 riding over a scale 46 by means of which a desired portion may be established.

In addition to the device thus far described I preferably use in my method a stabilizer illustrated in Figures 5 and 6, which may be formed integral with a cap 47, the latter preferably being in the nature of a bathing cap. The stabilizer which may be secured to the cap by means of two intersecting metal straps 48 curved to the curvature of the human head, comprises a platform 49 fixed to the straps, a second platform 50 pivoted at one end to ears 51 rising from the first platform, and held in adjusted relation relative to the other end of the platform by means of a bolt 52, a wing nut 53 and a spring 54 interposed between the two platforms. A third platform 55 is secured to the second platform in a similar manner but for transverse movement by means of the ears 56 at one end and the bolt 57, the spring 58, and the wing nut 59 at the other end. This third platform has mounted thereon, preferably with freedom of revolving motion a frame 60 having two spaced arms 61 and 62 revolvably supporting a shaft 63, having a calibrated wheel 64 thereon adapted to register with a point 65 on one of the arms 62. The shaft 63 has pivotally supported thereon a pointer 64' supporting a magnetic compass 65' at its lower end terminating in a quadrant pointer 66 at its upper end, the latter being adapted to ride over a scale 67, provided on a cross piece 68 supported between the arms 61 and 62. In order to place the stabilizer in the same position on the head at a subsequent time, a pencil mark may be made on the cap and on the head so that when the cap is again placed on the head the cap mark may be brought into the same relative position with the head mark as it formerly occupied.

To carry out the method I first raise the platform 1 so that the slot 7 approximately corresponds to the horizontal eye plane of the patient. I then cause the patient to step in place in the manner shown in Figure 1, with his face directed toward the mirror and spaced therefrom by about eighteen inches. I now cause the patient to stand in upright position with his arms hanging down freely, and cause him to close his eyes and to turn down his head as if to look at the floor. The patient raises his head with his eyes still closed until he thinks that his eyes are directed toward the distant horizon. I have

found by experiment that a person may perform this operation any number of times, and will always find that at the end of the operation his head is in substantially the same position.

The patient now opens the eyes and looks at the mirror. If by looking toward the mirror he finds that the pupils of his eyes see the light 5 through the narrow slot 7, the device is in the correct position. If the slot 7 is either above or below the correct position, the operator lowers or raises the platform 1 until the slot 7 and the light 5 are in the correct position, and may be seen by the patient in alignment with the pupils of his eyes. The slots 22 in the ends and the partitions of the boxes are all in alignment with the slot 7, and serve the purpose of eliminating stray light rays so that only those rays emanating directly from the light toward the slot 7 are observed by the patient. After the apparatus has thus been adjusted to the proper elevation, the slot 7 and the slots 22 establish the horizontal plane of the pupils of the eyes of the patient.

The next operation serves the purpose of bringing the head into proper position relative to the median vertical plane of the apparatus. For this purpose the slots 22 in the box are covered up by means of the slides 23, and the two boxes 8 and 9 are separated by means of the screws 12 until the holes or apertures 25 previously described are brought into alignment with the pupils of the eyes of the patient, which operation, of course, may require not only an adjustment of the two boxes to make the distance between the apertures 25 register with the distance between the pupils of the patient's eyes, but also adjustment of the head of the patient to bring the same in the proper position relative to the median vertical plane of the apparatus. The openings 6 of the light chamber are preferably covered by windows of different colors such as red and green to facilitate orientation of the patient.

After this operation has been performed the head has been adjusted so as to cause its median plane to coincide with the median vertical plane of the apparatus, and the operator now proceeds to establish the third plane, namely a transverse vertical plane defined by the glabella, the most anterior part of the forehead. To establish this plane, the patient positions his forehead in the manner illustrated in Figure 1 against the lower end of the pendulum 35, and advances the latter against the opposition of the weight 40 until the pendulum occupies a vertical position as may be ascertained from the position of the pointer on the scale. The purpose of the weight is to give a standard compression of the soft tissues in front of the glabella so that the transverse plane coincides as nearly as possible with the actual front portion of the skull.

The three planes thus established, namely the horizontal plane of the pupils, the median plane of the pupils, and the transverse plane of the glabella, meet at a point within the skull shown at 69, and this is the cranial point of orientation which it is the object of my invention to establish.

For slight corrections of the head posture, I may use the additional apparatus illustrated in Figures 3, 5 and 6. The apparatus shown in Figure 3 may be used for controlling slight side motions of the head which might be made by the patient without losing sight of the slot 7 because the latter naturally has to have a certain width

which allows of slight shifting of the pupils. The weighted pendulums 42 placed against the sides of the head seem to successfully eliminate such side movements. Cross hairs such as are used in surveyors' tools, transits, etc. placed in the slots would accomplish the same purpose but according to my experiments registrations obtained by the aid of the weighted pendulums are very satisfactory. The weighted pendulums 42 also aid in establishing the median plane of the pupils where the patient has only one good eye. The boxes 8 and 9 are adjusted until the proper aperture 25 is brought into alignment with the one good eye. The side pendulums 42 cause the head to assume a vertical position and take the place of the bad eye.

For further improving the results, I preferably also use the stabilizer shown in Figures 5 and 6 which may be adjusted by means of the wing nuts 53 and 59 to bring the wheel 64 and the pointer 64' into central positions relative to their respective scales so that any movement of the head made after adjustment will be immediately apparent to the operator. The stabilizer is also provided with a magnetic compass 65 to advise the operator of any turning movement carried out by the head after adjustment. The stabilizer is also used for accurately positioning the person's head in the same position it occupied with reference to the device on a previous occasion. The three scales lying in three different planes permit accurate adjustment to be made.

My method of and apparatus for establishing the cranial point of orientation may be rendered useful in many different ways to establish certain desired measurements of the human cranium, and one simple method is illustrated in Figure 1 of the drawing.

It is assumed in this drawing that it is desired to fix different points of the occlusal plane relative to the cranial point of orientation. For this purpose I have the patient take a bite, the bite 70 having a fixed arm 71 extending therefrom and a receptacle 72 being fixed relative to the apparatus in such a manner that the end of the arm 71 extends thereto. After the head has been positioned in the manner shown in Figure 1, the container 72 is filled with plaster of Paris to hold the arm 71 in the fixed position. If the head is now carefully removed from the position shown in Figure 1, the bite 70 remains in exactly the same position. The operator may then proceed by any suitable means to physically fix the point of orientation defined by the three planes previously referred to, and may then take the desired measurements as indicated by the dotted lines. In a similar manner a plaster mask might be applied to the outside of the head, and fixed in place so that upon removal of the head desired dimensions or measurements might be made from the established point of orientation. In either case the patient may subsequently place his head in the same position formerly occupied. In the first instance the patient by again taking the bite in his mouth would reposition his head exactly where it formerly was. In the second instance, the placing of the patient's head in the cast would accomplish the same purpose. It is obvious that other markings could be resorted to. If desired, of course, the bite might be removed to another place, and the point of orientation located and physically fixed at such other place by means of data obtained from the apparatus.

It should be noted from Figure 4 that a mag-

netic needle 69' is mounted on top of the device for the purpose of orientating the machine.

The pivot points 43 can be bolts adjustably mounted in slots 43' so as to accommodate heads of different widths between the pendulums 42. Scales, not shown, may be placed on the arms 41 adjacent to the slots to facilitate the positioning of the pendulums. It will also be noted that the portions of the pendulums 35 and 42, contacting with the head, are provided with rollers 35'. The device does not rotate when the screw 2 is actuated for raising or lowering it. After the device has been moved vertically into the desired position by the screw 2, it may be rigidly connected to the screw by a small set screw, not shown, and in this way the device is held against rotation while it is being used. It is obvious, as has already been set forth, that the point of orientation in the cranium can be obtained if the person has only one eye instead of two. In this event the horizontal plane will pass through the good eye and the vertical plane will also pass through the same eye. The transverse front plate will be in the same position as that occupied when the point of orientation is midway between the two eyes.

I claim:

1. An apparatus for establishing a cranial point of orientation comprising a platform, means for raising and lowering the same, a mirror arranged vertically on the platform and having a horizontal slot therein, a light chamber rearwardly of the mirror and spaced therefrom and having a light opening toward the mirror, and a box interposed between the mirror and the light chamber and having slots in horizontal alignment with the slot of the mirror.

2. An apparatus for establishing a cranial point of orientation comprising a platform, means for raising and lowering the same, a mirror arranged vertically on the platform and having a horizontal slot therein, a light chamber rearwardly of the mirror and spaced therefrom and having a light opening toward the mirror, and a pair of boxes interposed between the mirror and the light chamber on opposite sides of a vertical median plane, each box having a series of aligned eye holes in the plane of the slot and the boxes having means for uniformly moving the same in opposite directions toward or away from the median plane.

3. An apparatus for establishing a cranial point of orientation comprising a platform, means for raising and lowering the same, a mirror arranged vertically on the platform and having a horizontal slot therein, a light chamber rearwardly of the mirror and spaced therefrom and having a light opening toward the mirror, and a pair of boxes interposed between the mirror and the light chamber on opposite sides of a vertical median plane, each box having a series of aligned eye holes in the plane of the slot and the boxes having means for uniformly moving the same in opposite directions toward or away from the median plane, with expandable means for closing the space between the boxes to the rays of the light chamber.

4. An apparatus for establishing a cranial point of orientation comprising a platform, means for raising and lowering the same, a mirror arranged vertically on the platform and having a horizontal slot therein, a light chamber rearwardly of the mirror and spaced therefrom and having a light opening toward the mirror, and a pair of boxes interposed between the mirror and

- the light chamber on opposite sides of a median vertical plane, each box having slots in horizontal alinement with the slots of the mirror and means for covering the slots, each box also having 5 a series of alined eye holes in the plane of the mirror slot, and means for uniformly moving the boxes in opposite directions toward or away from the median vertical plane.
5. In an apparatus for establishing a cranial 10 point of orientation, means for determining the horizontal plane of the eyes and comprising a support, a vertical mirror carried thereby and having a slot extending horizontally across the same and means connected to the support for 15 raising and lowering the mirror for bringing the slot into the plane of the real and reflected pupils of the eyes of a person looking into the mirror.
6. In an apparatus for establishing a cranial 20 point of orientation, means for determining the horizontal plane of the eyes and comprising a support, a vertical mirror carried thereby and having a horizontal slot thereacross with a light 25 behind the slot, and means connected to the support for raising and lowering the mirror for bringing the slot into the plane of the real and reflected pupils of the eyes of a person looking into the mirror.
7. In an apparatus for establishing a cranial 30 point of orientation, means for determining the horizontal plane of the eyes and the median vertical plane between the eyes, said means comprising a support, a vertical mirror carried thereby and having a horizontal slot thereacross with 35 a light behind the slot, and a pair of members mounted on the support and on opposite sides of a median vertical plane of the apparatus and movable in a horizontal plane in opposite directions at equal speeds and having holes moving in 40 the line of the slot and transversely to the line of sight for positioning the head of the person relative to the median plane when the holes are the same distance apart as the pupils of the eyes.
- 45 8. An apparatus for establishing a cranial point of orientation comprising a support, a vertical mirror carried thereby, and having a horizontal slot thereacross with a light behind the slot, means connected to the support for raising 50 and lowering the mirror for bringing the slot into the plane of the real and reflected pupils of the eyes of a person looking into the mirror, a pair of members mounted on the support and at opposite sides of a median vertical plane of the apparatus and movable in a horizontal plane and in 55 opposite directions, said members having holes moving in the line of the slot, and transversely to the line of sight for positioning the head of the person relative to the median plane when the holes are the same distance apart as the pupils of the eyes.
- 60 9. An apparatus for establishing a cranial point of orientation comprising a support, a vertical mirror carried thereby, and having a horizontal slot thereacross with a light behind the slot, means connected to the support for raising 65 and lowering the mirror for bringing the slot into the plane of the real and reflected pupils of the

eyes of a person looking into the mirror, a pair of members mounted on the support and at opposite sides of a median vertical plane of the apparatus and movable in a horizontal plane and in opposite directions, said members having holes 5 moving in the line of the slot, and transversely to the line of sight for positioning the head of a person relative to the median plane when the holes are the same distance apart as the pupils of the eyes, and means carried by the support bearing against the glabella under predetermined pressure for establishing a frontal transverse plane of the head that extends at right angles to the median plane and to the horizontal plane. 10

10. An apparatus for establishing a cranial 15 point of orientation in three planes and comprising a support, a horizontal indicator, means secured to the support for positioning the horizontal indicator level with the eyes for establishing a horizontal plane, means on the support for 20 positioning the eyes equal distances from a vertical median plane, and means connected with the support for establishing a transverse frontal plane, the intersection of these three planes determining the cranial point of orientation. 25

11. An apparatus for establishing a cranial 30 point of orientation in three planes and comprising a support, a horizontal indicator, means secured to the support for positioning the horizontal indicator level with the eyes for establishing a horizontal plane, means on the support for 35 positioning the eyes equal distances from a vertical median plane, and means connected with the support for establishing a transverse frontal plane, the intersection of these three planes determining the cranial point of orientation, said second named means having means associated therewith for indicating any slight side tilt to the head and for compressing the soft tissues at the sides 40 of the head. 45

12. An apparatus for establishing a cranial 50 point of orientation in three planes and comprising a support, a horizontal indicator, means secured to the support for positioning the horizontal indicator level with the eyes for establishing a horizontal plane, means on the support for 55 positioning the eyes equal distances from a vertical median plane, and means connected with the support for establishing a transverse frontal plane, the intersection of these three planes determining the cranial point of orientation, said second named means having means associated therewith for indicating any slight side tilt to the head and for compressing the soft tissues at the sides 60 of the head, the means for establishing the transverse frontal plane having means associated therewith for compressing the soft tissues at the front of the head. 65

13. An apparatus for establishing a cranial 65 point of orientation in three planes and comprising a support, a horizontal indicator, means secured to the support for positioning the horizontal indicator level with the pupil of an eye, means on the support for establishing a vertical plane so as to pass through the same pupil, and means connected with the support for establishing a transverse frontal plane, the intersection of these three planes determining the cranial 70 point of orientation.

EDGAR W. SNELL.
